DESIGN FOR A GAME BOARD OR THE LIKE

Norris G. Wiltse, Jr., and Glenn Sinkule,
Ypsilanti, Mich.

Application September 25, 1942, Serial No. 108,338

Term of patent 7 years

To all whom it may concern:

Be it known that we, Norris G. Wiltse, Jr., and Glenn Sinkule, citizens of the United States of America, residing at Ypsilanti, in the county of Washtenaw, State of Michigan, respectively, have invented a new, original, and ornamental Design for a Game Board or the like, of which the following is a specification, reference being had to the accompanying drawing, forming a part thereof.

Portions in Figure 1 are shaded to indicate contrasting colors.

We claim:

The ornamental design for a game board or the like, substantially as shown and described.

NORRIS G. WILTSE, JR.
GLENN SINKULE.
